UNITED STATES PATENT OFFICE

2,517,201

LIQUID FOR TREATING MOTION-PICTURE FILM

Bernhard Grüter, Lucerne, Switzerland, assignor
to Klar-Film A. G., Zurich, Switzerland

Application March 1, 1945, Serial No. 580,315

3 Claims. (Cl. 106—271)

1

The present invention relates to a motion picture apparatus combined with sound producer and especially to a new and improved method to make used picture film bands more translucent after the same has become dull and scratched after much use. This operation is performed shortly before the use while the film band passes the gate of a film projector. The invention relates moreover to a device to automatically perform the said operation while the images of the film band are being projected. The invention is applicable also to sound or talking films projectors.

The object of the invention is to improve the reproduction of sound and images and I attain the object by moistening the film band shortly in advance of the gate of the projector by which the projection of the images is performed. The moistening is effected by means of a non-ignitable fluid having the same or nearly the same refraction of light as the material of which the film band consists. A liquid adapted for the said purpose is for instance a halogenised hydrocarbon and more particularly carbon tetrachloride.

Carbon tetrachloride like all the halogenised hydrocarbons would make the film band in a very short time brittle and of no further use. To obviate this drawback, natural wax for instance bees wax or carnauba wax is added to the halogenised hydrocarbon. This addition keeps the film band pliable.

Halogenated hydrocarbons have a pungent odor. It is therefore advisable to add some perfume, for instance eucalyptol or eucalyptus oil or gum. The addition of the last said means and especially of eucalyptol have moreover a very marked effect on the improving action of the tetrachloride. Other means for instance lavender oil or pine needle oil may be used to cover the odor of the carbon tetrachloride.

It has been found that good results are obtained by the addition of .10 per cent of wax and .50 per cent of perfume.

Example.—0.8 gram of wax, heated in a hot water bath are dissolved in 100 grams carbon tetrachloride and after cooling further 800 grams of carbon tetrachloride and 5 grams eucalyptol are added. The resulting liquid is passed on to cushions of felt or the like by which the liquid is evenly distributed on the film band.

It has been found by experience that a film band treated as described may be used for about 3,000 performances while a non-treated film band is generally used only 400 to 500 times. The sound films may be reproduced free of any ac-

2

companying noise and the reproduction of a picture film are free of any colored stripes and the like.

In the accompanying drawing two examples of a device to treat the film according to the process described are shown in a diagrammatical manner:

Figs. 1 and 2 are side elevations of a device destined for narrow film bands.

Fig. 3 shows the means for applying the fluid to the film band in section and on a larger scale.

Fig. 4 is a section taken on line 4—4 of Fig. 3.

Fig. 5 illustrates in a diagrammatical the run of a film band of standard width through the projecting apparatus.

Fig. 6 shows the device to apply the fluid on to the film band, the broken lines illustrate the lid in its opened position.

Figs. 7, 8 and 9 are sections taken on the lines 20 7—7, 8—8 and 9—9 of Figs. 5 and 6 on a larger scale.

On a base plate a standard 2 is arranged carrying at its upper end a container 3 for the fluid by means of which the film band is cleaned. On 25 the standard 2 a hollow arm 5 is adjustably mounted by means of a clamp 4 which may be closed by screw 6. The arm 5 may be adjusted lengthwise and may be turned about its axis. The tubular arm 5 is provided at its free end with a ball shaped head 7. On the latter a casing 8 is adjustably mounted. In the casing 8 two cushions 9, 10 of fluid adsorbing material for instance porous rubber are arranged. In a wall of the casing 10 four screw threaded bores 11 are 30 arranged. In two of said bores 11 on both sides of the cushions 9, 10 a guideroller 18 is mounted by a pin (Fig. 3). A film band 12, which is to be cleaned and which has to pass between the cushions 9, 10 runs over the said rollers 18. The cushion 10 is arranged on a holder 14 hinged to the casing 8 by a pin 13. On said pin a torsional spring 15 is arranged which tends to press the cushion 10 against the cushion 9. By pressing on a handle 16 the cushion 10 may be passed downwards and the film band 12 may be positioned between said cushions 9, 10 and on the rollers 18.

To retain the cushions 9, 10 apart a sprung stop 16 is fastened to the wall of casing 8. The free end of the stop 16 may pass over a nose 17 on the lid 14 after the latter has been pressed down. By means of a button 19 (Fig. 4) the stop 16 may be brought out of engagement with said nose 17 freeing thereby the lid 14 which is brought to bear on the film band 12 and on cushion 9 by the 55 expanding spring 13. Between the lid 14 and

the cushion 10 leaf springs 15^a are arranged which allow the cushion 10 to bear with its full upper face on the film band 12 pressing same on to cushion. The liquid to clean and to improve the transparency of the film band 12 which is stored in the receptacle 3 passes by a tube 20 and pipe 5 through bore 21 to the cushion 9. The flow of the liquid can be controlled by a hand operated valve 24. A small tube 22 arranged in the container 3 opens into atmosphere by a bore 23 in the valve body 24.

The new device may be used in connection with many types of film projectors, the casing 8 may be placed in any appropriate position. The film band 12 passes from the spool 26 through the casing 8 and over guide rollers through the window D of the projecting apparatus 25 and passes on to the spool 27. The liquid from the container 3 under a small head fills both the cushions 9, 10. The film band 12 is moistened and cleaned. The vapors escaping are dangerous to the health of the operators, they are removed below the gate by means of a nozzle 80 connected by a tube 81 with a sucking-off ventilator 82 and therewith with a tube leading to a chimney or into atmosphere. The casing 8 extinguishes moreover the film band 12 should the same by accident catch fire.

The device shown in Figs. 1 to 4 might be well used for narrow film bands 12, while the device shown in Figs. 5 to 9 is adapted to clean and to clear wider film bands 12.

The device 8 to moisten the film band 12, is connected by a tube 58 to a liquid container 31 arranged at the wall 32 adjacent the spool 26, 33. In the tube 58 a valve 34 is arranged to control the flow of liquid to the device 8. The latter comprises two cushions 40, 41 of loose felt through which liquid may pass. The film band 12 which passes on to the window D is led over the guide rollers 42, 43, 44 rotatably mounted in the casing 45, it passes between the cushions 40, 41 to a roller 46 leaving the casing 45 over a roller 47. The cushion 40 is held fast in the casing 45 by needles 50 fixed to the said casing. The cushion 41 rests on blade springs 51 and held near the film band 12. To press said cushion 41 on to the film band a roller 55 is rotatably mounted in bearings 54 of the lid 53. If the lid 53 is in closed position, the roller 55 presses the blade springs 56 on to the back of the cushion 41 and presses the latter on to the film band 12. The cushion 41 resting on the said springs 56 adapts itself and presses with its full upper face on the film band 12. Liquid is fed by the tube 58 from the container 31 into channels 57 at the back wall of the cushion 40. To keep the film band 12 taut, the

5 roller 43 is mounted on a lever 60 adjustably mounted on the casing 45. Near the gate D the nozzle 80 is arranged by which vapors are drawn-off and passes on to a chimney as described with reference to Figs. 1 to 4.

What I wish to secure by United States Letters Patent is:

10 1. A liquid for rendering scratches on motion picture film temporarily invisible, consisting of a non-ignitable halogenized hydrocarbon having substantially the same index of refraction as the film and having a wax in the amount of .10 per cent by weight dissolved therein.

15 2. A liquid for rendering scratches on motion picture film temporarily invisible, consisting of carbon tetrachloride and having a wax in the amount of .10 per cent by weight dissolved therein.

20 3. A liquid for rendering scratches on motion picture film temporarily invisible, consisting of carbon tetrachloride having a wax in an amount of .10 per cent by weight dissolved therein and containing an amount of an odorous oil sufficient to overcome the objectionable odor of said carbon tetrachloride.

25 BERNHARD GRÜTER.
